UNITED STATES PATENT OFFICE.

JOHN DOLPH, OF BAY CITY, MICHIGAN.

BARREL-SCALES.

SPECIFICATION forming part of Letters Patent No. 258,287, dated May 23, 1882.

Application filed August 6, 1881. (No model.)

To all whom it may concern:

Be it known that I, JOHN DOLPH, of Bay City, in the county of Bay and State of Michigan, have invented an Improvement in Scales, of 5 which the following is a specification.

The nature of this invention relates to certain new and useful improvements in the construction of scales which are especially designed to be employed in the filling of salt or 10 other barrels and to determine the quantity 15 which the barrels shall contain.

In the scales heretofore employed the platform often becomes bound against the frame within which it has its movement, and therefore 20 by hindering the effective working of the scale; and the object of this invention is to so hang the platform as to obviate this difficulty; and to that end the invention consists in the peculiar construction, arrangement, and combination 25 of the parts, all as more fully herein-after set forth.

In the accompanying drawing, which forms a part of this specification, and in which my invention is shown in perspective, A represents a suitable frame to support the operating 30 parts of the scale, and which may be mounted upon suitable rollers or casters, if desired, so that it may be readily moved from place to place.

B represents the beam of the steelyard-scale, which may be graduated and provided with an adjustable weight, C, which may be secured to the position upon the beam by means of a set-screw, b. Pendent from the shorter arm of 35 this beam by means of a suitable hanging is the frame D, to the lower end of which is rigidly secured the platform E. At or near the four corners of this platform are rigidly secured the eyebolts d, with which is engaged one end of 40 the rods F, the opposite ends of which are properly secured to the lower portion of the frame A, they being arranged in such a manner as to hold the platform E free from and

to prevent its coming into contact with the frame at any point in its vertical movement 45 during the process of weighing.

It will be seen by this construction that the objections raised against the old style of scales are entirely avoided, and that the barrel may be filled with salt or other material to the exact weight determined by the position of the weight upon the lever, as the platform can in no way become bound within the frame. 50

I am aware that platform-scales have heretofore been supplied with stay-rods to prevent 55 the platform from becoming bound; but the platforms of such scales have a very limited movement, and therefore the stay-rods as used in said scales would not answer with my steel-yard-scale, owing to the greater movement of 60 my platform. My scale being especially adapted for weighing barrels containing salt or other weighty substances, it is very desirable to have the platform as near the floor as possible, in order to facilitate the movement of the barrels 65 to and from the platform, and by attaching the brace-rods to the frame and platform above the platform, as shown in the drawing, I am enabled to bring the platform much nearer to the floor than by any other arrangement of said 70 brace-rods.

What I claim as my invention is—

In a portable scale, the platform E, the steel-yard B, and the bifurcated yoke D, connecting the platform and steelyard, in combination with 75 the frame A, supporting the steelyard and provided with a base surrounding three sides of the platform, and the four stay-rods F, connected to four sides of the upper surface of the platform and to the three sides of the base at 80 points above the platform, substantially as and for the purpose specified.

JOHN DOLPH.
